In the Netherlands July 27, 1948

5 Claims. (Cl. 200—67)

1

The present invention relates to electrical switches and more particularly to switches for use in electric gramophones. Switches of the type to which the invention is directed comprise two movable contacts and associated control members so arranged that switching on and off is effected by actuating one of the control members.

It is an object of the invention to provide a novel switch construction wherein the contacts may be brought into an actuated position by either of the control members and can be returned to the rest position solely by a specific one of the two control members.

A further object of the invention is to provide a switch particularly adapted for use in electric gramophones, which switch is simpler to construct, is positive and foolproof in its action and is of low cost.

These and further objects of the invention will appear as the specification progresses.

The switch in accordance with the invention comprises two movable contacts and associated control members. Arranged between each contact and the associated control member is a coupling system. One of the coupling systems permits the control member to adjust the contact to either one of two positions whereas the other coupling system permits the control member to adjust the associated contact to solely one of two positions. In a preferred embodiment of the invention the coupling systems each comprise a kink spring which is so pivoted as to provide the above-noted degrees of movement of the contacts.

The invention will be described in greater detail with reference to the appended drawing forming part of specification and in which:

Fig. 1 is a schematic showing of an electrical switch in accordance with the invention.

Fig. 2 shows a modification of the switch of Fig. 1.

Fig. 3 schematically illustrates the construction of one of the contact and coupling systems of the switch of the invention, and

Fig. 4 is a cross-sectional view of a gramophone switch in accordance with the invention.

The switch shown in Fig. 1 comprises contact members 1 and 2, which are relatively movable in the manner of so-called "hammer" contacts, the contact surfaces being in this case at right angles to the direction of movement of the members. However, as an alternative, use may be made of contacts having abutting surfaces at an angle differing from 90°, for example as shown in Fig. 2.

2

With the interposition of kink springs 3 and 4 respectively, the latter being shown in Fig. 3, the contact members 1 and 2 are movable by means of separate switching arms 5 and 6 respectively, each having two operating positions. For this purpose the switching arms 5 and 6 are rotatable about spindles 7 and 8 respectively, secured in the housing of the switch, so that lugs 9 and 10 respectively, which are secured to the arm, are adapted to act upon the terminal part of the kink springs 3 and 4 respectively. The kink springs 3 and 4 respectively are furthermore pinched with a determined tension on blocks 11 and 12 respectively, which are secured to the housing of the switch and which extend through an aperture in each of the kink springs 3 and 4, the apertures being provided by tongues 13 and 14 respectively which are punched out of the springs 3 and 4 respectively and the free ends of the tongues, in the bent position, engage as knife edges grooves 15 and 16 respectively, provided at one side of the blocks 11 and 12 respectively, whereas the edges of the said apertures in the springs 3 and 4 respectively engage as knife edges grooves 17 and 18 respectively, provided at the opposite side of the blocks 11 and 12 respectively. The springs 3 and 4 are connected through leads to a voltage source.

The coupling between the first switching arm 5 and the kink spring 3 is such that displacement of the arm 5 from the position shown into the position shown by dotted lines, and conversely, has the effect that a moment turning to the left or to the right with respect to the block 11 is exerted on the terminal part of the kink spring 3, resulting in a constrained spring tension variation as required for kinking the spring.

The coupling between the second switching arm 6 and the associated kink spring 4 is such that upon displacement of the arm from only one of the positions towards the other, i. e. from the position shown in full lines into the position shown in dotted lines, a moment is exerted relative to the block 12 on the terminal part of the spring 4, resulting in the spring tension variation required for kinking and in the associated contact member 2 being pushed towards the other contact member 1. On moving the switching arm 6 back into the position shown, a moment is not exerted on the terminal part of the spring 4, so that the spring will not move.

The construction is such that in the position shown of the second switch arm 6 (switching-off position) the switch is open in the position shown of the first switching arm 5 and is closed when the last-mentioned arm occupies the posi-

tion shown in dotted lines. In the position shown of the arm 5, the switch may, as an alternative, be closed by moving the arm 6 into the position of this arm shown in dotted lines (switching-on position). The switch remains closed when the arm 5 is moved into the position shown in dotted lines, i. e. the position in which the switch is closed if the arm 5 alone, as described above, would close the switch. In this position the tensile force of the spring 4 is smaller than that of the spring 3, i. e. when the arm 6 is moved back into the switching-off position (shown), the switch remains closed since the two contact members 1 and 2 are jointly moved downwards by the difference in tensile force of the springs. When the arm 5 again undergoes a position variation, the switch will be opened.

In order to restrict the stroke of the contact members 1 and 2, the extremities of the springs 3 and 4 to which the contact members are secured, in the position in which the switch is open, engage fixed stops 19 and 20 respectively, which are provided in the housing of the switch.

The arm 6 is preferably subject to spring action in such manner that, in order to obtain the aforesaid switching-on position, the arm must be moved against the action of this spring. This involves that, after being moved into the on-position (shown in dotted lines), the arm 6 automatically returns to the position shown, so that in the case last described the switch can be opened only by position variation of the arm 5. Furthermore, the first arm 5 will not be capable of opening the switch when the second arm 6 occupies the on-position. In this case both contact members would jointly move upwards.

It is thus possible to close the switch by position variations of both switching arms, but to open it in all circumstances by position variation of the arm 5. This is important if the switch is used for switching on and off the current for a gramophone motor. Such a switch is shown in Fig. 4. In the position shown the switch is open. The switching arm 5 of Fig. 1 is replaced by a support 21 for the pick-up arm 22. The fixed block 11 of the said figure is replaced by a movable block 23, which is rotatable about a shaft 24 and which forms part of the support. A blade spring 25, of which one end is secured to the housing of the switch at 26 and the other end to the block 23, forces the support to occupy the position shown in dotted lines. The switching arm 6 of Fig. 1 constitutes a manual switching lever 27, which is urged into the position shown by the above-described spring 28. The springs 3 and 4 are connected to a voltage source through the spring 25 and through a lead respectively. The operation of the switch is as follows.

As soon as the pick-up arm is lifted, the support moves, under the action of spring 25, into the position shown in dotted lines with the result that the required kinking tension is produced in the spring 3 and the contact member 1 moves downwards to close the switch. As soon as the pick-up arm, for example, after a gramophone record has been played, is placed on the support, the latter returns to the position shown, the contact member 1 moves upwards and the switch is opened again. While the pick-up arm lies on the support, the motor current may yet be switched-on by moving the switching lever 27 into the position shown in dotted lines. Thus, the tension variation required for kinking is

produced in the spring 4, so that the contact member 2 moves upwards and the switch closes. When the lever 27 is released, it moves under the action of spring 28 back into the position shown without involving the tension variation in the spring 4 required for kinking. Consequently, the contact member remains in the rest position. When the pick-up arm is now lifted, the required kinking tension is produced in the spring 3 owing to the change in position of the support 21 and both contact members jointly move downwards, so that the switch remains closed. As soon as the pick-up arm has been placed again on the support, the contact member 1 moves upwards so that the switch is opened.

What I claim is:

1. An electrical switch comprising first and second movable contact members, first and second control members, a first coupling member interposed between said first contact member and said first control member and being arranged to move said first contact member to first and second positions corresponding to first and second positions of said first coupling member, and a second coupling member interposed between said second contact member and said second control member and being arranged upon movement of said second control member from first to second positions thereof to solely move said second contact member into contact with said first contact member at the first of the said positions of said first contact member.

2. An electrical switch comprising first and second contact members movable in abutting relationship, first and second control members, a first kink spring member interposed between said first contact member and said first control member, said first control member acting on said first kink spring member to move said first contact member to first and second positions corresponding to first and second positions of said first control member, said second control member having first and second positions, and a second kink spring member interposed between said second contact member and said second control member, said second control member acting on said second kink member between movement of said second control member from first to second positions thereof to solely move said second contact member into contact with said first contact member, said second kink spring having a tensile force smaller than the tensile force of said first kink spring.

3. An electrical switch comprising first and second movable contact members, first and second control members, said first control member comprising a support rotatable about a given axis, a first kink spring member interposed between said first contact member and said support of said first control member, said first control member acting on said first kink spring member to move said first contact member to first and second positions corresponding to first and second positions respectively, of said first control member, and a second kink spring member interposed between said second contact member and said second control member, said second control member acting on said second kink spring member between first and second positions thereof to solely move said second contact member into contact with said first contact member at the first of the said positions of said first contact member.

4. An electrical switch comprising first and second movable contact members, first and second

control members, said first control member comprising a support provided with knife edge mounting grooves on opposite sides thereof and being rotatable about a given axis, a first kink spring coupling member having one end thereof secured to said first contact member and comprising a tongue portion, said tongue portion of said spring engaging the grooves of said support, the end of the spring remote from the contacts engaging said first control member to thereby move said first contact member to first and second positions corresponding to first and second positions of said first coupling member, a fixed support member provided with knife edge grooves in opposite sides thereof, and a second kink spring coupling member having one end thereof secured to said second contact member and comprising a tongue portion, said latter tongue portion and said second spring engaging the grooves of said fixed support, said second control member engaging said second spring between movement from first to second positions thereof to solely move said second contact member into contact with said first contact member at the first of the said positions of said first contact member.

5. An electrical switch comprising first and second movable contact members, first and second control members, said first control member comprising a support provided with knife edge mounting grooves on opposite sides thereof and being rotatable about a given axis, a first kink spring coupling member having one end thereof secured to said first contact member and comprising a tongue portion, said tongue portion of

15
